CARRYING CARTON

Stuart P. Sanford, West Orange, N.J., assignor to Westinghouse Electric Corporation, East Pittsburgh, Pa., a corporation of Pennsylvania

Filed Nov. 4, 1957, Ser. No. 694,366

6 Claims. (Cl. 206—65)

This invention relates to containers and, more particularly, to a carrying carton adapted to compactly unitize a plurality of articles for shipment and sale and thereafter attractively display and render them conveniently portable by the purchaser.

In the shipment and merchandising of certain types of goods, especially those of small size which are purchased in groups rather than singly, it has been found desirable from both a handling and sales standpoint to combine a number of the articles in a suitably designed wrapper or container and thus provide an aggregative unit or so-called "pack." Unitized packaging of this character has been extensively adopted in the electric lamp industry for lamp types which are generally purchased in lots by the customer, such as photoflash lamps for example. It has accordingly become standard practice to insert a readily saleable number of photoflash lamps in a suitably apertured platform which holds the lamps in planar base-to-base relation and then slip the entire assembly into a tightly-fitting sleeve of corrugated packaging material to provide a flat multi-lamp pack of convenient size. Should the customer desire to purchase a greater number of lamps than that contained in a single pack he is obliged to purchase a number of such packs thereby necessitating the expenditure of additional time and material by the dealer to wrap or otherwise package them.

There is a need, therefore, for a carton which will not only hold a plurality of items having substantially flat surfaces such as multi-lamp packs but which is of such construction that when loaded it can be readily and compactly stacked for bulk shipment to and shelf storage by the retailer and thereafter conveniently conditioned to render the articles portable by the consumer without the need of further packaging. It would also be a definite advantage from an advertising and sales-promotional standpoint if the packaged articles could be exposed to the view of prospective buyers by the retailers to provide an attractive display, if desired, and when being carried by the purchaser.

It is accordingly the general object of the present invention to provide a container adapted to receive a plurality of articles and retain them in convenient shipping and carrying arrangement with a minimum amount of packaging material and a maximum degree of viewability.

Another object of the invention is the provision of an improved carrying carton whereby a plurality of articles may be economically and compactly unitized for bulk shipment, storage and sale and upon receipt by the retailer attractively displayed to prospective customers, if desired, and rendered conveniently portable when sold.

A more specific object of the present invention is the provision in an open-ended carrying carton of content-retaining means which may be conveniently and economically formed as an integral part of the carton and easily or automatically disposed to interlockingly engage the edge of a smooth-surfaced article when the carton is set up for loading.

The aforesaid objects, and others which will become apparent as the description proceeds, are achieved by providing a collapsible open-ended tubular casing or sleeve of relatively stiff sheet material having marginal edge portions that are disposed to serve as content-retaining means, and a central portion designed to be conveniently displaced

2

from the body and contour of the carton and locked in upstanding relation to provide a handle and leave an attractive display window.

A better understanding of the invention may be obtained by referring to the accompanying drawings wherein:

FIG. 1 is a perspective view of one form of carrying carton assembled and ready for loading according to the invention;

FIG. 2 is an end sectional view through the carton taken on the line II—II of FIG. 1, as viewed in the direction of the arrows, illustrating the spatial relation between the main body and retaining portions of the carton and a plurality of vertically stacked articles according to one possible loading arrangement afforded by this embodiment of the invention;

FIG. 3 is a fragmentary view in perspective and on an enlarged scale of the lower and forward-facing right-hand corner of the carton, as viewed in FIG. 1, illustrating in greater detail the content-retaining elements according to this embodiment of the invention;

FIG. 4 is a plan view on a reduced scale of the blank from which the carton shown in FIG. 1 is formed;

FIG. 5 is a perspective view on a reduced scale of the carrying carton shown in FIG. 1 as it would appear if collapsed flat for bulk shipment from the supplier to the user;

FIG. 6 is a view corresponding to that shown in FIG. 1 but illustrates the handle and content-retaining portions of the carton during an intermediate phase of their assembly;

FIGS. 7, 8 and 9 are fragmentary top sectional views of the carton shown in FIG. 1 illustrating the manner in which an article is loaded and retained therein;

FIG. 10 is a view corresponding to FIG. 1 but illustrates an alternative embodiment of this invention;

FIG. 11 is an end sectional view through the carton taken on the line XI—XI of FIG. 10, as viewed in the direction of the arrows, illustrating the loading arrangement according to this modification of the invention;

FIG. 12 is an enlarged fragmentary view in perspective of the upper and rearward-facing right-hand corner of the carton, as viewed in FIG. 10, illustrating in greater detail one of the content-retaining elements according to this form of the invention;

FIG. 13 is a view similar to FIG. 4 but illustrates the construction of the blank employed in accordance with the alternative embodiment of the invention; and

FIG. 14 is a view corresponding to that shown in FIG. 5 but illustrates the manner in which the alternative form of carton contemplated by this invention folds flat for bulk shipment.

While the invention may be advantageously employed to compactly and portably unitize any group of articles suited to this type of handling and merchandizing, it is especially adapted for use in packaging electric lamps such as a plurality of photoflash lamp packs or individually packaged photoflood lamps and the like which while relatively bulky are light in weight.

Referring now more particularly to the drawing, in FIG. 1 there is shown a carrying carton A according to one form of the invention which carton comprises generally an open-ended sleeve or tubular container of rectangular configuration having an integral handle assembly 44 and inturned marginal tab-like members or flaps 23, 30, 32 and 34 at each end thereof which serve as content-retaining elements. The carton A may be conveniently fabricated from a single piece of substantially rigid sheet stock, such as paperboard or the like, that has been cut and scored to form a generally rectangular blank 16 of the character illustrated in FIG. 4. As will be seen from the drawing, the blank 16 is divided by a series of transverse and parallel spaced score lines 19

into a plurality of rectangular panels which, when considered from the aspect of their ultimate function and in the order of their appearance, may be defined as a connecting panel 18, side wall 20, top wall 22, side wall 24 and bottom wall 26, as viewed in FIG. 1. The corners of the blank 16 are mitered so as to provide V-shaped notches 39 at selected corners of the carton A which is formed when the blank is subsequently assembled and disposed in tubular formation in the manner hereinafter described. The sides of the connecting panel 18 may be similarly mitered and the panel coated with suitable adhesive, as shown in FIG. 4, to facilitate the assembly operation.

The side or peripheral edge portions of the above-mentioned wall-forming panels 20, 22, 24 and 26 are further divided by longitudinal cut-and-score lines 29 and centrally-located V-shaped notches 31 into a series of marginal tabular members or flaps 28, 30, 32 and 34 referred to above. The foregoing cut-and-score lines 29 are desirably formed by alternately slitting and scoring the blank material along a line which parallels the side of the blank 16 and connects the points at each corner thereof where the mitering begins so that the marginal flaps thus defined are of substantially equal depth or width. The V-shaped notches 31 are coincident with and symmetrical about the transverse score line 19 joining the top wall 22 with the side wall 24 and of sufficient depth that they bisect the aforesaid marginal tabular portions thereby dividing said portions into four continuous and separately-foldable flap elements 28-30 and 32-34 which each include a corner-forming section of the blank 16.

To facilitate carrying the loaded carton a centrally located handle assembly 44 is provided. As shown in FIG. 4, this assembly is formed from medial portions of the blank 16 and comprises, in general, matching grip-forming portions 46 and an anchoring portion 48 defined by weakened or perforated tear lines 43 and 47, respectively. The anchoring portion 48 as here shown is hat-shaped to provide three tabular extensions and constitutes a centrally-located upper segment of the side wall 20. The grip-forming portions 46 are formed from two adjoining and similarly shaped sections of the side wall 20 and top wall 22 which sections are symmetrical about the score line 19 joining said walls and foldable therewith into overlapping relation. The connecting parts of the grip-forming portion 46 within the top wall 22 and furthest removed from the said score line 19 taper inwardly toward each other and terminate abruptly in transverse outwardly-extending recesses thereby forming two pairs of ear and slot elements 52 and 54, respectively, in the top wall 22 at the marginal edge portions thereof located at the base of the grip-forming portion 46. The center of the grip-forming portion 46 struck from the top wall 22 is removed to provide a D-shaped handle aperture 50 of approximately the same size as the crown of the hat-shaped anchoring portion 48 struck from the side wall 20 thereby enabling said grip-forming portions to be grasped when folded in overlapped relation as hereinafter described. Score lines 55 at the root of the grip-forming portion 46 struck from the top wall 22 serve to hingedly connect the handle assembly 44 to a medial portion of said top wall, preferably along the centerline thereof. The anchoring portion 48 is similarly hingedly connected to the grip-forming portions 46 by means of score lines 51 which parallel the aforementioned score lines 55. Thus, an integral handle assembly 44 is provided which is easily displaced from the blank 16 and conveniently foldable into an upstanding two-ply handle which extends longitudinally of and is centrally-located with respect to the top wall 22.

In assembling the carton A according to this embodiment of the invention, the blank 16 shown in FIG. 4 is progressively folded along the transverse score lines 19 and the upwardly-facing marginal end portion of the bot-

tom wall 26 secured to the underside of the connecting panel 18, as viewed in the drawing, to form the collapsible open-ended tubular container or sleeve illustrated in FIGS. 1, 2, 5 and 6. The seam or joint thus extends along the bottom of the carton A enabling the side and top walls thereof to be neatly and conveniently imprinted with informative or decorative matter. The ends of the blank 16 may be fastened together by means of staples or with suitable adhesive, as here illustrated, or the edges of the bottom wall 26 and the side wall 20 may be secured in abutting relation by a piece of gummed tape, in which case the connecting panel 18 may be dispensed with. The opposing walls are preferably of the same size and contour so that the carton A may be collapsed flat for bulk shipment from the supplier to the user, as illustrated in FIG. 5, the carton as here shown being collapsed so that the bottom wall 26, side wall 20 and the juncture seam therebetween face upwardly as would be the case if the blank 16 were assembled by automated means well known in the art. It should be noted that the handle assembly 44 remains connected to and within the contour of the wall-forming panels of the blank 16 from which it is struck thereby permitting the cartons to be tightly packed for bulk shipment to the user and (after being loaded) to the retailer.

To prepare or set up the carton A for loading it is first distended from its "as-received" collapsed condition (FIG. 5) into tubular formation, as shown in FIG. 6, and the marginal flaps 28-30 and 32-34 folded inwardly along the cut-and-score lines 29. This operation may be most conveniently effected by slightly collapsing the carton A along the notched score line 19 and the one diagonally-opposite thereto and then pressing the flaps inwardly at the scored corner-forming portions thereof to thus snap them into the carton from their normally longitudinally-extending position, as shown in FIG. 6, to their operative inturned position illustrated in FIGS. 1 to 3 and 7 to 9. The carton A is then returned to its fully distended position and generally rectangular shape shown in FIGS. 1, 2 and 6, thus completing the setting-up operation. It will be noted that when set up in this fashion diagonally opposite corners at each end of the carton A are slit by V-shaped notches 31 and 39, respectively, the first mentioned being the V-shaped notches described above and the latter being formed by the mitered corners of the blank after it has been assembled into tubular formation. The marginal flaps 28-30 and 32-34 by virtue of their continuity and the fact that they each include a corner are locked in their inturned position within the assembled carton A and, due to the stiffness of the blank material, the parts of said flaps remote from said included corners resiliently spring away from their respective conjoined walls to form inwardly protruding retaining elements which features and relationships can best be seen in FIG. 3. Inasmuch as the aforementioned marginal flaps are coextensive with the peripheral edges of the carton A, this form of construction is ideally suited for holding (see FIG. 2) a plurality of vertically-stacked articles 62 having flat surfaces, such as a plurality of generally flat and rectangular photoflash lamp packs or the like. It will, of course, be understood that the wall-forming panels of the carton A are suitably dimensioned in cross-section to snugly receive the articles 62 when the latter are arranged in loaded position. This dimensional relation and the manner of loading is illustrated in FIG. 2 and in FIGS. 7 through 9, the latter being fragmentary top sectional views of the assembled carton A shown in FIGS. 1 and 2.

As illustrated in FIGS. 7 through 9, as each of the articles 62 is longitudinally inserted into the carton A the inturned marginal flaps (flaps 28, 32 and 34 as here viewed) at that end of the carton are depressed by the sides of the article and compressed flat against their conjoined wall-forming panels (side walls 20 and 24 and bottom wall 26, respectively). The articles 62 are forced

inwardly until they contact the protruding flaps (members 28, 32 and 34 as viewed in the drawing) at the opposite end of the carton A whereupon the flaps at the loading end spring away from their respective walls to provide an inwardly-protruding peripheral lip or flange which engages the outer edge portions of the articles 62 and locks said article in loaded position within the carton A.

As shown in FIG. 9, the overall length L1 of the carton A is such that the reduction thereof effected by the combined widths of the inturned content-retaining flaps 28-30 and 32-34 at each end provides an article-receiving space or "Loading" length which is just slightly longer than the length L2 of the articles 62 to be accommodated. Conversely, the width of the opening W1 defined by said flaps when in their inturned positions is considerably less than the width W2 of said articles and (as shown in FIG. 2) substantially shorter in height than the combined height of an integral number of vertically-stacked articles, for example five as in the case here illustrated. In this manner the articles 62 are individually and collectively snugly received by and locked within the carton A. The content-retaining flaps 28-30 and 32-34 by virtue of their continuity, rigidity and snapped-inturned relation with the main body portions of the carton A provide depressible cleats or lips which (1) not only bear against the peripheral end edges of the stacked articles 62 in line contact therewith and prevents them from accidentally falling out of the carton A when the latter is being carried but are (2) capable of being subsequently flipped into longitudinally-extending position (as shown in FIG. 6) to permit one or several of said articles to be conveniently withdrawn for use and (3) thereafter snapped back into the carton to retain the rest of the articles in their loaded positions as before.

Turning now to the handle assembly 44, after the carton A has been loaded as above-described and shipped to the retailer or subsequently sold, the matching grip-forming portions 46 and anchoring portion 48 are conditioned for use by simply displacing them from the top wall 22 and side wall 20 by separating the blank material along the weakened tear lines 43 and 47, respectively. The handle assembly 44 is then manipulated so that the grip-forming portions 46 are folded one upon the other in overlapping relation along the transverse score line 19 joining said top wall 22 and side wall 20 and the anchoring portion 48 disposed in planar relation with the side wall 20 and slipped between the inside surface thereof and the loaded articles 62 toward the top wall 22. In this manner the grip-forming portions 46 are progressively flattened one against the other during which time the anchoring portion 48 is maneuvered into planar relation with the top wall 22, as illustrated in FIG. 6.

Further displacement of the handle assembly 44 in the direction indicated in FIG. 6 forces the straight outwardly-facing edges of the grip-forming portion 46 struck from the side wall 20 to ride over the ears 52 provided in the top wall 22 and snap into the recesses 54 therebehind thus completing the operation and locking the handle assembly 44 in upstanding operative relation, as illustrated in FIGS. 1 and 2, due care being taken during this phase of the operation to slide the crown-like tabular extension of the hat-shaped anchoring portion 48 under the top wall 22. This latter interleaving arrangement in conjunction with the correspondingly disposed brim-shaped extensions not only serves to reinforce the top wall 22 but distributes the loading stress imparted thereto by the handle over a considerably greater area thus greatly increasing the load carrying capacity of the carton A. As will be obvious, the configuration of the anchoring portion 48 may be altered to enlarge its contacting area and distribute to an even greater degree the stress on the top wall 22 thereby proportionately increasing the rupture strength of the material. With the handle assembly 44 thus locked in upstanding position, an attractive display window 60 (FIGS. 1, 2 and 6) is pro-

vided through which the contents of the carton A may be viewed. This latter feature in conjunction with the open-end type construction employed provides in a very economical manner maximum viewability of the contained articles in the event the carton A is utilized as a display device and, in any case, when being carried by the purchaser. The handle assembly 44 is also capable of being retracted back into the contour of the carton A, if desired, by springing the grip-forming portions 46 from their interlocked relation with the ear and recess elements 52, 54 and simply reversing the procedure outlined above. Thus, the handle assembly 44 by virtue of its ability to be simply and conveniently disposed in operative position after loading preserves the rectangular contour of the carton permitting it to be compactly loaded for bulk shipment to and storage by the retailer.

In FIG. 10 there is illustrated an alternative form of the invention wherein a carton B of the same general configuration as carton A is provided. According to this embodiment, however, the blank 16a (FIG. 13) is divided by means of transverse score lines 19a into a series of rectangular panels proportioned to serve as a top wall 22a, side walls 20a and 24a and a pair of end panels 62 and 64 which, when joined together, form the bottom wall. With this type construction the juncture seam extends along a medial part of the bottom wall, as illustrated in FIGS. 10, 11 and 14, thus facilitating the manufacture, printing and assembly of the blank 16a by automated box-making equipment well-known in the art. Each side of the blank 16a is longitudinally divided in this case by score lines 63 and V-shaped notches 65 provided at alternate ones of the aforementioned transverse score lines 19a into separately foldable marginal flaps 66, 67 and 68. The V-shaped notches 65 (as shown in FIG. 13) are coincident and symmetrical about the transverse score lines 19a which join the top wall 22a with the side wall 20a and the other side wall 24a with the adjoining end panel 64. A plurality of triangular-shaped recessed webs 72 are provided in the flaps 67 and 68 at the ends of the other of said transverse score lines 19a by appropriately notching and scoring the material thereat to form a plurality of truncated V-shaped notches 70 and paired outwardly-diverging score lines 71, the latter forming continuations of the sides of said notches and meeting at the aforementioned longitudinal score lines 63. Inasmuch as each of the above-described web structures are identical, only the divergent score lines 71 in the upper marginal flap 68 of the blank 16a, as viewed in FIG. 13, have been identified by reference numeral. Only those sections of the marginal flaps 66, 67 and 68 which project beyond the line connecting the peripheral edges of the webs 72 are coated with suitable adhesive material so that the desired result hereinafter described may be obtained.

A handle assembly 44a comprising a hat-shaped anchoring portion 48a and matching grip-forming portions 46a is struck from the side wall 20a and top wall 22a and rendered foldably displaceable therefrom by suitable tear lines 43a, 47a and score lines 51a, 55a in the same fashion as described above in connection with carton A. Ear and slot elements 52a and 54a are also provided in the top wall 22a at the base of the grip-forming portion 46a struck therefrom to lock the handle assembly 44a in upstanding position as before. According to this design, however, instead of removing a part of the grip-forming portion 46a struck from the top wall 22a to form a handle aperture, a tear line 73 is provided (see FIG. 13) which, when said grip-forming portion is disposed in operative position, provides a handle aperture 50a as before and leaves a similarly shaped tongue 74 projecting from said wall, as shown in FIGS. 10 and 11.

Assembly of the blank 16a according to this form of invention is effected by first folding the marginal flaps 75 66, 67 and 68 downwardly, as viewed in FIG. 13, into

inturned overlapping relation with the corresponding adjoining wall-forming panels of the blank and securing them thereto by means of the aforesaid adhesively coated sections to provide the lapped peripheral edge structure shown in FIGS. 10, 11, 12 and 14. The blank 16a is then progressively folded, as in the case of carton A, along the transverse score lines 19a and the upwardly-facing marginal end portion of the end panel 62 secured to the underside of the adhesively-coated tabular part of the other end panel 64, as said panels are viewed in FIG. 13, thus forming a tubular open-ended sleeve as before. The application of pressure along the transverse score lines 19a provided with the V-shaped notches 65 collapses the carton B thus formed rendering it ready for bulk shipment to the user, as illustrated in FIG. 14 (the carton B as here illustrated being rotated through an angle of 360° from its "as-assembled" position after completion of the foregoing folding operation on the blank 16a when the latter is disposed as shown in FIG. 13).

An important feature according to this embodiment of the invention is the construction and mode of operation of the content-retaining means. As stated above, the triangular-shaped webs 72 are purposely left unattached and are defined by pairs of appropriately oriented score lines 71. In the assembled carton B these webs by virtue of the foregoing construction and manner of assembly constitute collapsible gussets at diagonally-opposite corners at each end of the carton B. When the carton B is distended into tubular formation preparatory to loading (see FIGS. 10 and 11), the rigidity of the blank material and the manner of scoring causes the gusset-forming webs 72 to automatically spring away from the walls and protrude inwardly, which characteristic can best be seen in FIG. 12, thereby forming compressible content-retaining elements adapted to engage diagonally-opposite corner edge portions of a rectangular-shaped and slightly undersize article 90, as shown in FIG. 11. Since the aforesaid content-retaining elements are located at oppositely-disposed corners only, this construction (in contrast to the marginal flap arrangement described in connection with carton A) effects what may be termed "point" retention so that the articles must be arranged in double layer and preferentially single layer formation. This manner of retention can, therefore, be most advantageously employed when the articles to be unitized are more or less cubical in form and lend themselves to horizontal rather than vertical stacking, such as a group of incandescent lamps of the photoflood type, for example, which lamps are individually packed in cubical paperboard containers. As will be appreciated, the "loading" length of the carton B is so proportioned that an integral number of such articles can be snugly accommodated therein between the aforesaid webs 72 when the latter are in distended position. It will, of course, be obvious that when the carton B is cross-sectionally dimensioned to snugly receive a single row of articles, one such corner-gripping element at each end of the carton would be sufficient to retain the articles in their loaded position, but at least two such elements at each end and at diagonally-opposite corners, as here illustrated, are preferred.

The handle assembly 44a is conditioned for use in the same manner as in carton A, the only difference being that the tongue 74 left in the top wall 22a extends into superimposed and edge-coinciding relation with the anchoring portion 48a, as illustrated in FIGS. 10 and 11, thus affording a greater area of overlap or interleave between these elements and even further strengthening the top wall 22a against rupture without the utilization of any additional material. As in the case of carton A, disposure of the handle assembly 44a in operative position provides an attractive display window 69a into the interior of the carton B, as shown in FIGS. 10 and 11.

As will be obvious from the foregoing, the objects of the invention have been achieved by providing an open-ended carrying carton adapted to compactly utilize a

5 plurality of articles and form a merchandizing unit which may be readily shipped, stored and attractively displayed and by providing integral content-retaining and handle means for such a carton capable of being quickly and simply assembled to render said articles conveniently portable by a purchaser.

10 While the present invention has been described in some detail by way of illustration and example for purposes of clarity of understanding in accordance with the patent statutes, it is understood that various changes and modifications may be made without departing from the spirit and scope of the invention. For example, while the articles have been illustrated and described as being rectangular in form, cylindrical shaped articles such as cans or bottles or the like and other items of non-rectangular configuration may be packaged in accordance with the principles of the invention by suitably proportioning the walls of the carton and contouring the content-retaining elements to snugly receive said articles when in vertical 15 or horizontal stacked relation and abuttingly engage the outwardly-disposed peripheral edges thereof.

20 I claim:

25 1. A tubular open-ended carton enclosing a row of articles each of which extend longitudinally of said carton and have their ends located at and disposed inwardly from the open ends thereof; said carton comprising a top and a bottom wall, a pair of side walls, and means retaining said row of articles in loaded position within said carton; said article-retaining means comprising an inturned flap 30 of relatively stiff material at each end of said carton resiliently hinged to and coextensive with one of said side walls and one of the walls joined thereto, the intermediate corner-forming portion of each of said inturned flaps by virtue of the continuity and stiffness of said flaps being 35 biased toward and nestingly seated against the respective corners of said carton thereby locking said flaps in inturned position, and the remaining portions of said flaps by virtue of the resiliency of the hinged juncture thereof with said carton being sprung away from the walls thereof 40 into abutting engagement with the ends of each of the packed articles, whereby said row of articles is interposed between and locked in loaded position within said carton by the upstanding portions of said flaps.

45 2. The combination of a tubular open-ended carton and an enclosed row of articles as set forth in claim 1 wherein said carton and article-retaining flaps are formed from an integral scored blank.

50 3. The combination of a tubular open-ended carton and an enclosed row of articles as set forth in claim 1 wherein a pair of said flaps are provided at each end of said carton and the upstanding portions thereof constitute a peripheral retaining lip at the ends of said carton that projects toward and is seated against the peripheral end surfaces of said row of articles.

55 4. A collapsible tubular open-ended carton of relatively stiff material enclosing a single row of articles stacked in side-by-side relation along the axis of said carton with the outermost articles located at and disposed inwardly from the open ends of said carton; said carton comprising a 60 top and a bottom wall, a pair of side walls, and means retaining said single row of articles in loaded position within said carton; said article-retaining means comprising a continuous flap at each end of said carton that is hinged to adjoining side walls thereto and includes an 65 intermediate triangular-shaped web element defined by divergent score lines that extend from the corner formed by said adjoining side walls to the edge of said flap, each of said flaps being inturned into said carton and, with the exception of said web element, being permanently attached to the respective side walls in overlapped relationship therewith, said unattached web elements by virtue of the rigidity of the carton material comprising erectable gussets that automatically spring away from the walls of 70 said carton when the latter is set up for use and constitute 75

projections that engage a corner of the outermost articles and thus lock said row of articles within said carton.

5. The combination of a tubular open-ended carton and an enclosed single row of articles as set forth in claim 4 wherein said carton and flap members are formed from 5 an integral cut and scored blank.

6. The combination of a tubular open-ended carton and an enclosed single row of articles as set forth in claim 4 wherein a pair of automatically erectable gussets are provided at each end of said carton at diagonally opposite 10 corners thereof.
